UNITED STATES PATENT OFFICE

94,455

DESIGN FOR A NEEDLEWORK BASKET

Zella Wallis, Chicago, Ill., assignor to Wm. H. Molter Company, Chicago, Ill., a corporation of Illinois

Application October 27, 1934, Serial No. 53,795

Term of patent 3½ years

To all whom it may concern:

Be it known that I, Zella Wallis, a citizen of the United States of America, residing at Chicago, in the county of Cook and State of Illinois, have invented a new, original, and ornamental Design for a Needlework Basket, of which the following is a specification, reference being had to the accompanying drawing, forming a part thereof.

I claim:
The ornamental design for a needlework basket, substantially as shown.

ZELLA WALLIS.
